ABSTRACT OF THE DISCLOSURE

A mercury thermometer constructed to facilitate the reading of temperatures has the entire interior bore portion including the bulb coated with a fluorescent material. The empty bore portion under magnification will appear dull and it will appear more intense in color or brightness when the bore contains the mercury. The scale gradations and numerals may also have brightening elements associated therewith to read the mercury level more easily.

The invention relates to thermometers, but more specifically to clinical thermometers mercury filled adapted to have the mercury column more easily read as: in varied positions; under normally trying light conditions in the sick room or otherwise; as an aid to those having less than normal eyesight; and as an aid to placement in proper reading position.

One of the objects of the invention in addition to the above considerations is to facilitate the taking of the user's own temperature reading whether in the sick bed or otherwise.

The above objects and other ends of the invention will hereinafter appear.

Accompanying this specification is a drawing showing a preferred form of the invention wherein:

FIG. 1 is a view in elevation of a thermometer embodying the invention herein;

FIG. 2 is an enlarged sectional view of FIG. 1 taken along the plane 2—2 thereof;

FIG. 3 is a fragmentary sectional view taken across the plane 3—3 of FIG. 2;

FIG. 4 is a fragmentary view in elevation taken from the plane of 4—4 of FIG. 2;

FIG. 5 is an enlarged sectional view of FIG. 1 across the plane 5—5 thereof;

FIG. 6 is a fragmentary view in section taken across the plane 6—6 of FIG. 5; and

FIG. 7 is a fragmentary view in elevation taken from the plane 7—7 of FIG. 5.

In accordance with the invention and the preferred form shown, a conventional clinical mercury thermometer 10 has a normal vertical column 11 in bore 12 terminating in bulb 12a, divisions 13 and numerals 14 being etched into the glass column 15.

2

A fluorescent coating material 16 of any desirable and effective color lines bore 12, the lining being accomplished by any known method of deposition or other application. A coating material 17 is also applied to divisions 13 and numerals 14, said coating material 17 being preferably fluorescent, but not being necessarily the same as in bore 12 colorwise or chemically, but having the property of making the divisions and numerals stand out brilliantly as compared to the conventional pigment fill.

Thus, when viewing column 15 head on, the glass area indicated by numeral 18 in FIG. 2 serves as a magnifier and enlarges bore 12. Where the bore is empty of mercury, the bore is faintly seen as indicated by numeral 19 in FIG. 4. Where the bore has mercury, the bore is seen brightly as indicated by numeral 20 in FIG. 7.

It is understood that minor changes in the device described and operation thereof may be resorted to without departing from the spirit of the invention and the scope of the appended claims.

I claim:

1. In a glass thermometer having a bore in the body thereof communicating with a bulb of mercury at the bottom of said body, said bore being adapted to receive a mercury column therein, said body having etched gradations and numerals on the surface adjacent said bore, in combination, a bore having a complete inner lining of colored fluorescent material to effectuate increased visibility of the top of the mercury column in said bore from any vantage point.

2. In a glass thermometer as set forth in claim 1 wherein the gradations and numerals are filled with fluorescent material.

3. In a glass thermometer as set forth in claim 1 wherein the thermometer body has a magnifying front wall.

4. In a glass thermometer as set forth in claim 1 wherein the thermometer body has a magnifying front wall and wherein the gradations and numerals are filled with fluorescent material.
